COMBINATION TOILET PREPARATIONS
DISPENSER

Gordon Wadsworth, Chicago, Ill.

Application September 25, 1940, Serial No. 358,307

4 Claims. (Cl. 221—79)

The present invention relates to toilet preparation dispensers and is particularly concerned with an improved device of this character wherein a toilet preparation, such as tooth paste, soap, or shaving cream, may be supplied in limited quantities in accordance with the needs of the user.

The principal object of the present invention is to provide a dispenser adapted to receive a container in which the toilet preparation is commercially packaged and to provide means for ejecting the preparation from the container in limited and controlled amounts. A further object is to provide a dispenser of this character which includes means for perforating the preparations container to provide an outlet for the preparation. A further object, and one which is particularly directed to the matter of sanitation, is to provide a dispenser which acts externally on the preparations container in ejecting the 20 contents.

In carrying out my invention, the preparation, which may be in paste or powder form, is packaged in a cylindrical container closed at one end in the fashion of an ordinary tin can. The other end of the container, after the container has been filled, is closed by a cooperating disc or piston which closely abuts the inner sides of the container. The end of the container closed by the disc or piston is bent inwardly upon itself to securely hold the disc in place on top of the preparation in the container. My dispenser is adapted to receive the container, to perforate the closed end thereof and to provide means for urging the opposite end closing disc lengthwise of the container with the result that the preparation is forced out through the perforation.

A further feature of the present invention is the utilization of the dispenser actuating member to open the outlet during the time the preparation is being forced from the container. At such time as the device is not being used the actuating member covers the outlet and prevents any of the preparation from falling out under the action of gravity. The presence of the outlet closing feature is also desirable from the standpoint of sanitation.

In the accompanying description and drawings, I disclose one possible embodiment of my invention. It is my idea that a combination including a plurality of individual dispensers and compartments for miscellaneous items, such as shaving equipment and tooth brushes, is a logical commercial embodiment of my invention.

Other features and advantages of the present invention will appear as the description proceeds, reference being had to the accompanying drawings wherein this preferred embodiment is shown. It is to be understood, however, that the drawings and description are not to be taken to limit the invention except insofar as it is limited to the claims.

In the drawings

Fig. 1 is a view in front elevation of my dispenser;

Fig. 2 is a plan view in partial cross section of the combination embodying the present invention;

Fig. 3 is a sectional view on the line 3—3 of Fig. 1, but showing the door in open position;

Fig. 4 is a sectional view on line 4—4 of Fig. 1;

Fig. 5 is a fragmentary sectional view on the line 5—5 of Fig. 1 showing the details of a unit dispenser;

Fig. 6 is a fragmentary sectional view on the line 6—6 of Fig. 1 showing a slight modification in my dispenser unit;

Fig. 7 is an enlarged sectional view showing the construction of the screw means which urge the disc or piston longitudinally of the container, and

Fig. 8 is a sectional view on the line 8—8 of Fig. 6.

Referring now to the drawings, and particularly to Figs. 1—4 thereof, a plurality of dispensers 10, 11 and 12 are mounted, by means of brackets 13, at spaced intervals on a back board 14. Compartments 15 and 16 are disposed between adjacent dispensary units. The compartments have bottoms 17 and 18, respectively, and side walls 19 and 20, respectively. The compartments are further defined by tops 21 and 22, respectively, and swinging doors 23 and 24. The doors 23 and 24 may be semi-cylindrical to harmonize with the cylindrical shape of the dispensers 10, 11 and 12. Hasps 25 are provided on each door and cooperate with grooves 26 in the bottoms of the compartments to provide means for locking the doors in closed position.

For purpose of illustration, tooth brushes 30 are supported by means of bracket 31 in the swinging door 23 of the compartment 15. As will be noted, considerable space within this compartment is provided to accommodate miscellaneous articles. A shaving brush 33 is mounted by means of bracket 34 in the swinging door 24 of compartment 16. Within the compartment, bracket 35 receives safety razor 36, and recep-

tacle 37 is provided to receive discarded razor blades. Other uses for the space within the compartments will no doubt occur to users of the combination.

Referring now to Fig. 5, my improved dispenser comprises an upstanding cylindrical member 40 having exterior threads 41 of limited length at the upper end. A cap member 42 is received by the threads 41 and is adapted to be more or less permanently associated with the member 40. A tubular member 43 having a knurled enlarged top portion 44 extends downwardly through a central opening in the cap 42. The knurled portion 44 rests on the top of cap 42 and annular flange 45 on the tubular member 43 cooperates with said knurled portion to retain the said member 43 in proper longitudinal relationship with said cap 42. As will be understood, the tubular member 43 may be rotated with respect to the fixed cap 42. A ratchet wheel 46 is fixedly mounted on the tubular member 43 to impart rotary motion thereto as hereinafter described.

The lower end of the cylindrical member 40 is enlarged as shown at 50 and the enlarged portion is provided with interior threads 51. A bottom cap member 52, somewhat similar to the top member 42, has its end exteriorly threaded to engage the threads 51 of the member 40. The cap member 52 has a central opening 53 in its bottom and a circular knife 54 extending upwardly from the edge of said opening. The upper edge of the knife is sharpened whereby to penetrate the bottom of an inserted container. As will be understood, before the cap member 52 is screwed to the member 40, the container is forced down into the cap member so the circular knife 54 is forced through the container bottom and, since the knife has a lower portion that is flat and not sharp, the cut out portion of the container bottom is bent upwardly as indicated at 55.

In order to impart rotary motion to the ratchet wheel 46, I provide a series of pivoted link members terminating in pawl 60 which engages the ratchet wheel 46 as clearly shown in Fig. 5. The shank 60' of the pawl 60 extends through opening 61 in the cap member 42 and is pivotally connected to link 62, which link is pivoted to arm 63 projecting from the side of cap member 42. Fixedly associated with the link 62 at the second mentioned pivot is link 64, which link has its free end pivotally connected with link 65 which extends substantially the length of cylindrical member 40. A fixed arm 66 projects from the lower portion of cylindrical member 40. Pivoted thereto is link 67. The free end of the link 65 is pivotally connected to the link 67 near the mid point of said link 67. An arcuate link 68 is pivoted to the free end of link 67 and terminates in an enlarged portion 69 adapted to cover the opening 53 in the bottom of the cap member 52. Lug 70 projects downwardly from the enlarged portion 69 to provide means for manually actuating the above described series of links. A spring member 71 projects downwardly from the cap member 52 for the purpose of removably retaining the link 68 and enlarged portion 69 thereof in close association with the bottom of cap member 52.

As will appear from the dotted lines in Fig. 5, the lug 70 is intended to be pushed rearwardly of the dispenser unit and, through the above described series of links and pivots, to impart rotary motion to the ratchet wheel 46. In order to remove the lower cover member 52, the link 68 may be swung away from its retaining spring

member 71, thereby clearing the way to unscrew the said cap member.

Contained within the tubular member 43 is a series of telescoping tubular screw members 75, 76 and 77. The construction of the series of telescoping screw members is somewhat similar to that of the well known automobile jack. The lower end of tubular member 43 is provided with an interior annular flange 80, as shown in Fig. 7, which flange is interiorly threaded to receive the exterior threads of screw member 75. Annular flange 81 is provided at the upper end of screw member 75 to prevent said screw member from disassociating itself from the tubular member 43. The lower end of tubular screw member 75 is provided with an interiorly threaded flange 82 which receives the threaded screw member 76. The said screw member 76 has flange 83 to prevent disassociation with screw member 75. Similarly, the said screw member 76 has at its lower end interiorly threaded flange 84 which receives the screw member 77. The said screw member 77 has flange 85 to limit longitudinally displacement of member 77 with respect to member 76.

The free end of screw member 77 has associated therewith a container top engaging member 90. The member 90 is adapted to bear on said container top and urge said top downwardly as the above described telescoping means is extended under the influence of rotated tubular member 43.

Having thus fully described my improved dispenser unit, I now pass to the consideration of the container adapted for use in such dispenser unit. The container comprises a cylindrical member 95 having one end closed as shown at 96. Centrally of the closed end 96 there may be provided a cylindrical extension 97, the end closing portion 55 of which is perforated as previously described to provide an outlet for the preparation within the container. A disc member 98 closes the opposite end of cylindrical member 95 and is adapted to be slid longitudinally within the said member 95 in the fashion of a piston. The disc 98 may be provided peripherally with a rubber or the like material 99 to insure positive contact with the wall of the member 95. The disc member 98 is provided with spaced upstanding ribs 100 adapted to receive the member 90 carried by the screw 77 previously mentioned. The upper edge of the container cylinder 95 is bent inwardly upon itself as shown in 101 to provide means for holding the disc 98 in initial position within the container.

To operate my dispenser, the link 68 is first removed from the spring 71, thereby permitting removal of the lower cap 52 of the dispenser. Before a new container may be inserted in the dispenser, it is necessary to retract the screw members 75, 76 and 77. This is done by manually turning the knurled head 44 of tubular member 43. Before this may be done, however, it is necessary to disengage pawl 60 from the ratchet wheel 46. For this purpose I provide lever 105 associated with shank 60' of pawl 60. Slight elevation of the lever provides the necessary disengagement. After the screw members 75, 76 and 77 have been retracted within the tubular member 43, the old container is removed and a fresh container is inserted through the bottom opening of the cylindrical member 40. As the cap 52 is applied to the member 40, the circular knife 68 perforates the bottom 96 of the inserted container as hereinbefore described. The bearing member 90 carried by screw 77 is then moved down

until it is received between the spaced upstanding ribs 100 on the disc member 98 to prevent relative rotation of the parts. The link 68 is next brought into engagement with spring member 71, thereby bringing its enlarged end 69 over the outlet 53. As will be readily understood, actuation of the lug 70 in correspondence with the dotted lines in Fig. 5, causes rotation of the tubular member 43, thereby extending the screw members 75, 76 and 77. Such extension, of course, causes the disc member 98 to be urged downwardly within the cylindrical container 95, thereby forcing limited amounts of the preparation through the outlet 53.

A modification of my new improved unit is shown in Figs. 6 and 8. The general make-up of this dispenser unit is the same as the unit previously described, the only variation being in the means for imparting rotary motion to the ratchet wheel 46. In this case I provide a sliding bar 110 which moves vertically on the front side of my dispenser unit. Lug 111 projects from the bar 110 to provide means for manually actuating said sliding bar. Pipe straps or the like 112, pass around the sliding bar 110 to retain it in position on the front face of the dispenser. An arm 113 projects from the rear of sliding bar 110 into the dispenser through elongated opening 114. Link 115 has one end pivoted to the arm 113 and has its other end rigidly mounted to rotatable rod 116. Rigidly associated with rod 116 is link 117 having its free end pivotally connected to shank 118 which carries pawl 119. The pawl 119 engages ratchet wheel 46 as clearly shown in Fig. 6. When the sliding bar 110 is moved upwardly as indicated by the dotted lines in Fig. 6, the pawl 119 is displaced to the right and imparts rotary motion to 46. Lever 120 provides means for disengaging the pawl and ratchet wheel when it is desired to retract the telescoping screw means.

In connection with the lower cap member of the dispenser I have provided a horizontal outlet passage 125 which delivers the preparation at the front of the dispenser. The lower end of the sliding bar 110 normally covers the outlet end of the passage 125, but when the bar is slid upwardly to force some of the preparation out of the dispenser the covering is, of course, removed to permit a flow of preparation from the outlet.

From the above description it is believed clear that I have provided an improved dispenser of the class described wherein various preparations may be delivered in controlled amounts in accordance with the requirements of the user. The device, furthermore, substantially eliminates any possibility of wasting the preparation. The sanitation aspects of my improved device are believed to especially distinguish over prior device of this general character. There is no transferring of the preparation from its original container to the dispenser nor is there anything except a small cutting edge inserted into the original container used with my dispenser.

It is believed that the nature and advantages of the present invention and the manner of its use will be readily apparent to those skilled in this art. Having thus described my invention, what I claim as new and desire to secure by Letters Patent is:

1. A preparations dispenser comprising a container receiving member, caps closing the ends of said member, one of said caps being removable to permit insertion of a container, said removable cap having an outlet aperture and a cutter adapted to perforate the container in line with said outlet as said cap is being secured to said container receiving member, an extensible device within said member adapted to bear on the inserted container, and means for actuating said extensible device, said means including a portion covering said outlet aperture except when said means are actuated.
2. A preparations container and dispenser, said container comprising a body portion closed at each end, the closure of one end being a piston movable longitudinally of said body portion, said dispenser comprising a container receiving portion having an outlet aperture at one end and means to perforate said container in line with said aperture, an extensible device adapted to bear upon and longitudinally urge said piston of said container, and means for actuating said extensible device, said means including a portion covering said outlet aperture except when said means are actuated.
3. A preparations dispenser and container, said dispenser including a container receiving member, caps closing the ends of said member, an extensible device within said member and supported by one of said caps and adapted to bear on an inserted container, said extensible device comprising telescoping parts adapted to expand or contract by relative rotation of the opposite ends of said device, said container including an end closure comprising a piston provided with a seat for engagement with one end of said extensible device to hold said end against rotation, and means for rotating the opposite end of said device.
4. In a preparations dispenser and container, an extensible device within said dispenser and comprising telescoping parts adapted to expand or contract by relative rotation of the end parts, an imperforate piston closing one end of said container and adapted to receive an end of said extensible device and to hold said end against rotation, the opposite end of said container having an aperture which registers with an aperture in the dispenser, and a means for rotating the end of the extensible device remote from the piston, said means including a portion covering said aperture in the dispenser except when said means are actuated.

GORDON WADSWORTH.
